US00D948074S

(12) **United States Design Patent** (10) **Patent No.:** **US D948,074 S**
(45) **Date of Patent:** **** Apr. 5, 2022**

(54) **CASSETTE CLAMP FOR
ELECTROPHORESIS GEL CASTING**

(71) Applicant: **LIFE TECHNOLOGIES
CORPORATION**, Carlsbad, CA (US)

(72) Inventors: **Kyle Bulloch**, San Diego, CA (US);
Xin Mathers, Poway, CA (US)

(73) Assignee: **Life Technologies Corporation**,
Carlsbad, CA (US)

(**) Term: **15 Years**

(21) Appl. No.: **29/694,184**

(22) Filed: **Jun. 7, 2019**

(57) **CLAIM**

The ornamental design for a cassette clamp for electrophoresis gel casting, as shown and described.

DESCRIPTION

FIG. 1 is a front perspective view of a cassette clamp for electrophoresis gel casting showing our new design.

FIG. 2 is a back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a front perspective view thereof showing environmental structure.

The dash lines depict environmental subject matter and form no part of the claimed design. The dotted lines depict portions of the cassette clamp for electrophoresis gel casting that form no part of the claimed design.
